METHOD AND MACHINE FOR MAKING
CLOSURE CAPSJohn C. Gibbs, New York, N. Y., assignor to
Anchor Cap & Closure Corporation, Long
Island City, N. Y., a corporation of New York

Application January 25, 1939, Serial No. 252,741

24 Claims. (Cl. 153—2)

The present invention relates generally to the manufacture of closure caps and more particularly to a method and machine for making closure caps, having an inturned bead or wire edge at the bottom thereof.

For many years, closure caps have been made with a beaded edge to straighten the skirt of the cap, to conceal the raw edge and prevent rust, and to improve the appearance of the caps. The bead has been formed by stamping a hat-shaped blank and thereafter rolling the brim or flange upwardly on the outside of the skirt into a wire edge. This has the disadvantage of making both sides of the metal from which the cap is formed visible from the exterior of the cap. If the inside of the cap is coated yellow and the outside coated black, the resulting cap is black with a yellow bead at the bottom. The objection has been so great that during the last three or four years caps have been sold with an inturned wire edge which gives the solid color throughout the cap and exposes but one side of the metal forming the cap. It was found, however, that the method for making the caps with the outturned wire edge could not be used for the manufacture of caps with the inturned edges. The former were manufactured in rolling machines which were able to deliver several hundred caps a minute because it was a continuous rolling operation whereas the latter had to be manufactured on what is termed dial machines, an example of which is shown in my application Serial No. 168,536, filed October 12, 1937, now Patent No. 2,282,959, granted May 12, 1942, and which are operated at a much slower speed, in most cases less than half the speed of the rolling machines. In addition, the units are larger, more expensive and require more attention in operation and the same number of operators as a rolling machine. Hence, the cost of labor is practically doubled in the actual forming of the caps. As a result, the inturned edge caps have been generally sold at a higher price and at a lower profit than the regular types of caps. While the improved caps are conceded better and more attractive than the prior types of caps, they have not been adopted generally due to their higher cost of manufacture. To decrease costs, attempts were made to roll the usual flange of the hat-shaped blanks downwardly instead of upwardly, but the resulting caps were not satisfactory and the method was not a success.

The present invention aims to provide a machine which will roll an inturned wire edge or bead on a cup-shaped blank at the same speed as machines heretofore have rolled outturned wire

edges on closure caps, thereby enabling manufacturers to make inturned edge closure caps at the same cost as other types of caps.

An object of the present invention is to provide an improved method and machine for making closure caps with an inturned edge or wire.

Another object of the invention is to reduce the cost of manufacture of closure caps with an inturned bead.

Another object of the invention is to provide a machine and method for manufacturing closure caps with an inturned bead in a continuous, as distinguished from an intermittent, operation at a high rate of speed.

Another object of the invention is to provide an improved means for feeding caps to a forming machine.

Another object of the invention is to provide an improved means for ejecting or removing the caps from the machine.

Other and further objects of the invention will be obvious upon an understanding of the illustrative embodiment about to be described, or will be indicated in the appended claims, and various advantages not referred to herein will occur to one skilled in the art upon employment of the invention in practice.

A preferred embodiment of the invention has been chosen for purposes of illustration and description and is shown in the accompanying drawings, forming a part of the specification, wherein

Fig. 1 is a side elevational view of the machine;

Fig. 1a is a sectional view of a blank adapted to be operated upon by the machine to form a closure cap;

Fig. 2 is a top plan view of the machine;

Fig. 3 is a sectional view of one of the forming heads, illustrating details thereof taken on the line 3—3 of Fig. 1;

Fig. 4 is a fragmentary detail view illustrating the movement of the caps along the guideway of the feeding mechanism taken on the line 4—4 of Fig. 5;

Fig. 5 is a fragmentary side elevational view of the feeding mechanism shown in Fig. 4;

Fig. 6 is a sectional view along the line 6—6 of Fig. 4;

Fig. 7 is a sectional view along the line 7—7 of Fig. 4, illustrating means for stopping the flow of caps to the machine when desired;

Fig. 8 is a sectional view along the line 8—8 of Fig. 1 illustrating the first operation performed on the blank illustrated in Fig. 1a;

Fig. 9 is a sectional view along the line 9—9

of Fig. 1 illustrating the second operation performed on the blank;

Fig. 10 is a fragmentary sectional view illustrating details of the mechanism for ejecting blanks from the chucks after the first operations are performed, taken on the line 10—10 of Fig. 1;

Fig. 10a is an enlarged sectional view illustrating the operation of the mechanism shown in Fig. 10;

Fig. 11 is a fragmentary sectional view illustrating the removal of the caps from the first forming head, taken on the line 11—11 of Fig. 1; and

Fig. 12 is a fragmentary sectional view along the line 12—12 of Fig. 1 illustrating the third and final operation performed on the blank in making a closure cap.

Described generally the preferred embodiment of the machine, which illustrates one way of performing the method, comprises a cap feed shown generally at 1 in Fig. 1 for feeding the blanks 2 illustrated in Fig. 1a to a head 4 where the lower edge of the blank is turned inwardly as shown in Fig. 8 and immediately thereafter a screw thread is formed in the cap as shown in Fig. 9. The blanks are then ejected by the mechanism shown generally at 5 in Fig. 1 and illustrated in Figs. 10, 10a and 11. The partly finished caps are then delivered by a feeding mechanism 1a, similar to the feeding mechanism 1, to a second forming head 6 where the partially formed bead is completed as shown in Fig. 12. Thereafter the caps are ejected at 7.

Referring to the drawings, Figs. 4, 5 and 6 illustrate details of the cap feed shown generally in relation to the machine in Figs. 1, 2 and 3. There is a guideway 10 for the blanks 2 having a channel member 11 with removable strips 12 extending sufficiently far over the channel to partially cover the blanks as shown more particularly in Fig. 6. The blanks pass along the channel until they engage a pivotally mounted stop or holding means 14 which is operated to release one cap at a time in a manner to be described. A second stop 15 rotatably mounted on the pin 16 below the first stop has its lower end 17 extending into the channel and in the path of the blanks to stop and position the lowermost blank. The stop 15 is held in its operative position by means of a pin 18 mounted in a bracket 19 and held resiliently against the stop by a spring 20. The purpose of the cap feed is to deliver blanks one at a time to the chucks 21 moving in a circular path as shown in Figs. 3, 4 and 5. As will be noted in Fig. 5, the guideway 10 is inclined at an angle to the path of the chucks 21. Thus, the blanks are delivered in tilted position so that each chuck 21 may engage the skirt or flange of a blank to force it past the stop 15 and seat it on the chuck for the subsequent forming operations. In order to relieve strain on the blank when the chuck engages the skirt while moving at a rapid speed, a roller 22 is mounted on the lower end of the stop 15 by a pin 24. The roller 22, as shown in Figs. 4 and 5, extends into the path of the chucks 21. Preferably the relative position of the roller 22 and the chuck 21 is such that the roller 22 is engaged and pressed outwardly at or just prior to the engagement of the chuck with the front edge of the blank. In this way the blank is automatically released independently of any pressure applied to it directly by the chuck. The release of the stop 15 also automatically releases the stop 14 by the engagement of the upper end of the stop 15 in the V-shaped notch 25. Thus, as each chuck

passes, a blank is delivered to the chuck and a second blank is released by the stop 14 so that it may drop against the stop 15 and be held in position for the succeeding chuck. The stop 14 serves to keep the line of caps spaced from the forward blank which is in position to be delivered to a chuck.

In certain cases, it may be necessary to stop the feeding mechanism without stopping the forming machine. For this purpose, a mechanism is shown in Figs. 4, 5 and 7 adapted to be operated to prevent the caps from moving past it in the guideway 10. The mechanism comprises a pin 26 having a spring 27 tending to force it upwardly in the path of the blanks. The pin is held in ineffective position by a latch member 28 pivotally mounted at 29. A projection 30 fits under a collar 31 normally to hold the pin 26 in ineffective position. If the operator desires to stop the feed of caps, he presses the latch member 28 in the direction of the arrow which removes the projection 30 from under the collar 31 and permits the pin 26 to be forced into the guideway to stop the movement of caps. When it is desired to start the cap feed again, the collar 31 may be gripped to pull the pin out of the path of the blanks, in which case the latch member 28 is forced into its operative position by a spring 32 to engage and hold the pin in inoperative position.

The blank after being fed to the chuck 21 passes through the head 4, shown generally in Figs. 1 and 2 and in detail in Fig. 3, where the lower edge of the cap is turned inwardly, as shown in Figs. 3 and 8, and a screw thread is formed in the cap as shown in Fig. 9. Referring more particularly to Fig. 3 of the drawings, the head 4 comprises a supporting bracket 34 having a bearing 35 in which a shaft 36 is mounted by a nut 37. A stationary disc 39 is keyed to the shaft 36 at its opposite end and a rotating disc 40 is mounted on the shaft 36 through the intermediation of the roller bearings 41. The disc 40 has gear teeth 42 on its periphery which mesh with a gear 44 (Fig. 1) for driving the disc. A series of chucks 21 are rotatably mounted in bearings 45 spaced equidistantly adjacent the periphery of the rotating disc 40. Each chuck has a gear 46 meshing with gear teeth on the periphery of the stationary disc 39. As the disc 40 is rotated, the chucks 21 are rotated with it about the shaft 36 and are also rotated, by means of the gears 46 meshing with the gear teeth 47, about their own axes.

Each chuck 21 (Figs. 3, 8, 9 and 10) has a disc 48 forming a shoulder adjacent the lower edge of the blank and a ring 49 having a spiral groove 50 therein for forming a thread on the cap. The discs and ring are held in position by a flanged nut 51 threaded to the supporting shaft 52 for the chuck. The stationary disc 39 has a series of plates 54, 55 and 56 mounted adjacent its periphery with parts adapted to cooperate with the chuck for forming the turned edge and the thread in the blank as shown more particularly in Figs. 3, 8 and 9. The plate 55 has a groove fitting about the disc 48 on the chuck and adapted to bend the edge of the cap about the disc 48 on the chuck as shown more particularly in Fig. 8. While the plate 56 could be utilized for forming the thread, it is preferred to have a second section in the head 4 as shown in Fig. 9 with plates 54a, 55a and 56a in which the thread is formed. It will be noted in Fig. 9 that the plate 55a is substantially a continuation of the plate

68 with a groove for the inturned edge of the cap. The plate 56a, however, has a rib 58 which corresponds in slope or inclination to the groove in the chuck 21. The plates 54, 55 and 56 are held in position by a plate 59 bolted to the periphery of the disc 39. Plate 59 extends outwardly beyond the chucks 21 to hold the blanks in position thereon. A cover plate 60 extends over the entire mechanism as shown in dot and dash lines in Fig. 3. As the blanks on the chucks 21 pass about the disc 39, the edge of the blank is first turned inwardly and thereafter in a second stage the thread is formed in the cap in a continuous operation.

The mechanism for removing the partially finished caps from the head 4 and delivering them to the head 6 where the blanks are finished is shown generally in Fig. 2 and in detail in Figs. 10, 10a and 11. While the chucks 21 are smaller than the blanks 2, the removal of the blanks therefrom is not a simple problem by reason of the inturned flange on the bottom of the blank and the relatively sharp shoulder formed by the disc 48 over which the flange fits. In order to prevent any possibility of the blanks interlocking with the parts of the chuck during the removal operation, a ring 61 is mounted on the chuck having substantially the same size as the inturned flange of the blank. The ring 61 is supported by pins 62 which are moved in and out by a shoulder 64 on a pin 65 extending centrally and axially of the chuck shaft 52. The pin 65 is held in ineffective position by a spring 66 mounted in a recess 67 in the supporting shaft 52 of the chuck and pressing against a collar 68 on the pin 65. The end of the pin 65 is threaded to receive a nut member 69 which has a ball 70 mounted in the end thereof by means of a plate 71 secured in position by screws 72. The pin 65 is normally ineffective, but when the chucks reach the ejection point, the bearing or ball 70 on the end of pin 65 engages a cam 74 which compresses the spring 66 and forces the shoulder 64 against the ends of the pins 62 to centralize the ring 61 with respect to chuck 21 as shown more particularly in Fig. 10a. When the blank is thus centralized by the ring 61, there is no possibility of the flange of the blank interlocking with the disc 48 and the cap may be removed from the chuck.

The removal may be effected in any suitable manner but preferably cams 75 engage the bottom of the blank as shown more particularly in Figs. 10a and 11 to remove the blank from the chuck and to deliver it into a guideway 76. In order to prevent any possibility of the blanks dropping back into the head 4, a stop preferably in the form of a resilient button or detent is provided at 77 and a second stop or detent is provided at 78. If a blank should not go all the way into the guideway 76, the succeeding cap delivered by the succeeding chuck 21 will force it past the second detent and eliminate any possibility of its getting into the machine. The guideway 76 may have a removable cover or window where the caps may be removed for inspection.

The guideway 76, shown more particularly in Fig. 1, delivers the caps down to a cap feed 1a similar to the cap feed 1 and the cap feed 1a delivers the partially finished blanks to the chucks in the head 6 in a similar manner to that described in connection with the cap feed 1. Therefore, a further description of the cap feed for the second head is not necessary.

The forming head 6 is adapted to roll the inturned flange of the blank upwardly and outwardly against the flange or skirt of the blank to form an inturned bead or wire edge as shown more particularly in Fig. 12. The forming head may be substantially similar to the head 4 and may have plates 80 and 81 adjacent the periphery. The operation is different from that of the first head. In the first head, the thread and flange are both pressed inwardly. In the second head, the inturned flange has to be pressed outwardly. To effect this operation, the chuck ring 48a forces the inturned edge of the blank outwardly while the skirt of the cap is supported in the plates 80 and 81, as illustrated in detail in Fig. 12. The chuck and ring 48a force the inturned edge on the blank firmly against the skirt of the blank to form a completed inturned bead or wire edge. Only one side of the sheet metal forming the cap is visible from the exterior of the cap. The construction of the chuck 21a is different from chuck 21 among other respects in that the parts are held in position by a screw or bolt 82. Since the inturned edge of the blank has been turned upwardly to form an inturned bead or wire, there are no projecting parts likely to interlock with the chuck and hence the cap centering device shown more particularly in Figs. 10 and 11 is not desirable in connection with the ejecting mechanism of the second head, although such means could be used. The cam mechanism for removing the caps and the stops for the caps may be similar to those illustrated and described in connection with the first forming head and a description is not being repeated here. The rotating disc 40a (Figs. 1 and 2) is geared to the intermediate gear 44 which also meshes with the rotating disc 40 of the forming head 4. Thus the two forming heads are interconnected and timed with respect to each other. In this way the output of each is the same and the second forming head will be prepared to receive all blanks delivered by the first forming head.

In some cases it may be desirable to turn the machine over manually to ascertain if all the parts are in working order. For this purpose, an idling gear 84 on a stub shaft 85 meshes with the gear teeth 42 on the disc 40 and also with a gear 86 mounted upon main drive shaft 87 which has a socket 88 adapted to be engaged by an operating crank. The drive shaft 87 is driven by a suitable motor (not shown) to operate the machine. The bracket 90 adjustably held in position by the bolt 91 is adapted to accommodate different sizes of gears 40 and 84 and to permit accurate adjustment by the handle 90 so that the gears mesh properly for driving the machine.

In the operation of the machine blanks 2, illustrated in Fig. 1a, are delivered by a suitable stamping machine to the guideway 10 where the foremost cap rests against the lower end 11 of the stop 15 until a chuck 21 passes, entering the skirt of the tilted cap and simultaneously engaging the roller 22 to release the stop 15 and thereby permit the cap to move out of the guideway on the chuck 21. Operation of the stop 15 likewise operates the stop 14 to deliver another cap in a position to be engaged by the next succeeding chuck. The chucks 21 move with the rotating disc 40 about the stationary disc 39 and are rotated about their respective axes by gears 46 meshing with the gear 47 on the periphery of the disc 39. The blanks pass the forming plates 54, 55 and 56 where the plate 55 forms an in-

turned flange on the bottom of the blank as shown more particularly in Fig. 8. In a subsequent section of the forming head a plate 56a with a rib 58 thereon forms a continuous thread in the blank. After the thread and flange are formed, the chuck passes the delivery point where a cam 74 engages the end of the pin 65 which centers the ring 61 of the chuck, which in turn centers the blank on the chuck and prevents any interlocking of parts. The blank thus centered is engaged by the cams 75 which remove the blank from the chuck. Stops 77 and 78 (Fig. 11) prevents any possibility of the blanks dropping back into the forming head. The partially formed blanks pass through guideways 76 and are fed to a second forming head 6 where chucks 21a therein carry the blanks past plates 80 and 81 (Fig. 12). The ring 48a on the chuck 21a engages the in-turned flange and forces it against the skirt of the cap which is held in position by the plates 80 and 81 to form an in-turned bead or wire. Thereafter, the finished caps are delivered through the guideway 76a to any suitable machine for applying sealing liners.

It will be seen that the present invention provides a machine in which a screw thread is formed in the cap and the cap provided with an in-turned bead or wire edge in a continuous rolling operation. The caps may be manufactured with the speed of a rolling machine and bumping operations requiring dial feeding are completely eliminated. The caps may be made with the same labor cost as ordinary screw caps with outwardly rolled edges and thus a better product can be sold at the same price as the present less desirable form of cap. The machine is rugged in construction with little likelihood of the parts becoming disarranged or broken. It will be understood that while the present method and machine are shown applied to screw closure caps that it may be utilized in any instances where any in-turned bead or wire is desired, regardless of the other structural features added to the cap.

As various changes may be made in the form, construction and arrangement of the parts herein without departing from the spirit and scope of the invention and without sacrificing any of its advantages, it is to be understood that all matter herein is to be interpreted as illustrative and not in a limiting sense.

Having thus described my invention, I claim:

1. The method of forming a thread and an in-turned bead or wire in the manufacture of a closure cap or similar article, which method comprises spinning the lower edge of the cap blank inwardly, rolling the thread in the cap blank prior to the completion of the formation of the bead and completing the formation of the bead after the threading operation by turning said in-turned flange upwardly and outwardly against the skirt of the cap blank in a single continuous operation.

2. The method of forming an in-turned wire or beaded edge in the manufacture of a closure cap or similar article, which method comprises spinning the lower edge of the cap blank inwardly and in the same operation forming a screw thread in the cap blank, and thereafter in a substantially continuous movement of the cap, spinning said edge outwardly against the skirt of the cap blank to complete the formation of the bead.

3. In a device of the class described, the combination of means for feeding blanks for closure caps, a chuck to enter and carry a blank, means for turning the lower edge of the blank inwardly while on said chuck, a second chuck, automatic

means for removing the blank from said first chuck and placing it on said second chuck, means for forcing said in-turned edge upwardly and outwardly against the skirt of the cap blank while on said second chuck, and drive means for moving said chucks past the respective means effective thereupon.

4. In a device of the class described, the combination of means for feeding blanks for closure caps, a chuck to enter and carry a blank, means for turning a part of the metal of the blank inwardly while on said chuck, a second chuck, automatic means including guide members engaging the bottom of the blank for removing the blank from said first chuck and holders for removably supporting the blank in the path of said second chuck, means for forcing said in-turned part of the metal of the blank outwardly while on said second chuck, and a common drive for operating said chucks in timed relation with respect to each other.

5. In a device of the class described, the combination of means for feeding blanks for closure caps, a chuck adapted to enter and carry a blank, means for turning in the lower edge of the blank while on said chuck, means for forming a screw thread in said blank while on said chuck, a second chuck, automatic means including a guideway for removing the blank from said first chuck and holding it in position to be engaged by said second chuck, means for forcing said in-turned edge upwardly and outwardly against the skirt of the cap, and a common drive means for moving said chucks in timed relation with respect to each other past the respective means effective thereupon.

6. In a device of the class described, the combination of means for feeding blanks for closure caps, a chuck adapted to enter and carry a cap blank, means for rotating said chuck about its axis, means for engaging the lower edge of the blank on said rotating chuck to roll the lower edge inwardly, a second chuck, means for moving said chuck in different orbits and in timed relation to each other, means for rotating said second chuck about its axis, and means for removing the blank from said first chuck and holding it in the path of said second chuck whereby it becomes nested over said second chuck and means for cooperating with said second chuck to roll said in-turned edge upwardly and outwardly against the skirt of the cap to form a beaded edge.

7. In a device of the class described, the combination of means for feeding blanks for closure caps, a chuck adapted to enter and carry a blank, means for rotating said chuck, a stationary forming tool adapted to cooperate with said chuck, and means for moving said rotating chuck past said stationary forming tool to turn the lower edge of the blank inwardly, a second chuck, automatic means centering the blank about, and for removing the blank from said first chuck and placing it on said second chuck, a stationary forming tool for cooperating with said second chuck, means for rotating said second chuck, means for moving said second rotating chuck past said stationary forming tool to force said in-turned edge upwardly and outwardly against the skirt of the cap to form a bead.

8. In a device of the class described, the combination of means for feeding blanks for closure caps, a chuck adapted to enter and carry a blank for a closure cap, said chuck being of a smaller diameter than said blank, a stationary forming

tool adapted to cooperate with said chuck, means for rotating said chuck about its axis, means for moving said chuck past said stationary forming tool for turning in the lower edge of the blank to form an inturned flange and for forming a screw thread in the blank, a second chuck, automatic means for centering the blank about the first chuck to prevent interference between the flange and the chuck, means for removing the blank from said first chuck and applying it to said second chuck during the movement thereof, a stationary forming tool adapted to cooperate with said second chuck, means for rotating said second chuck and means for moving said second chuck past said stationary forming tool to complete the formation of the bead on said closure cap.

9. In a device of the class described, the combination of a chuck adapted to enter and carry a blank for a closure cap, said chuck being smaller than said blank, means cooperating with said chuck for turning in the lower edge of said blank about a part on said chuck, means for engaging said blank and centering it on said chuck so that the inturned flange on the blank will not engage said chuck in the removal thereof and means for removing said blank from the chuck.

10. In a device of the class described, the combination of means for feeding blanks for closure caps, a chuck adapted to enter and carry a closure cap, said chuck being smaller than a blank, means cooperating with said chuck to form an inturned flange at the bottom of said blank and means associated with said chuck and adapted to center said blank on the chuck at the time of removal to prevent the flange from interlocking with parts of the chuck during the removal operation.

11. In a device of the class described, the combination of means for feeding closure caps, a chuck for entering and carrying a closure cap, means cooperative with the chuck to force a portion of the skirt inwardly, expanding means including a ring member for engaging the lower edge of the blank to center the blank on the chuck and to prevent interlocking of the inwardly forced parts of the blank with parts of the chuck during the removal operation and means for operating said expanding means.

12. In a device of the class described, the combination of a chuck adapted to enter and carry a cup-shaped blank, means adapted to cooperate with said chuck to perform operations comprising the bending of parts of the blank from the exterior of the blank inwardly, a second chuck, means for centering the blank about the first chuck to prevent interference between the chuck and the inwardly bent parts of the blank and for transferring the blank from the first chuck to said second chuck and means cooperating with said second chuck to bend portions of said blank from the interior thereof outwardly.

13. In a device of the class described, the combination of a chuck adapted to receive a closure cap, means cooperating with said chuck and effective upon the exterior of the cap to form an inwardly extending thread in said blank and an inturned edge at the bottom of said blank, a second chuck, means for removing the blank with the inturned edge and thread from said first chuck and placing it on said second chuck and means cooperating with said second chuck to bend said edge upwardly and outwardly into a completed wire or beaded edge, and a common drive for operating said chucks.

14. In a device for feeding blanks for closure caps to a forming machine, the combination of a guideway, a chuck adapted to engage and enter the blanks in said guideway and for removing the blanks from the guideway, a member for resiliently holding a blank in position to be engaged by the chuck, a second member for holding a second blank spaced a substantial distance from said first blank so as to allow said chuck to move into said second blank without disturbing the position of said first blank, said first member being pivoted intermediate its ends to said guideway and having a portion adjacent one end thereof adapted to operate said first member and having means adjacent the other end thereof extending into the path of the chuck adapted to be operated by the chuck to release said first blank and said second blank to permit said second blank to replace the first blank after it is moved out of the guideway by the chuck.

15. In a device for forming an inturned bead on a closure cap or similar article, the combination of an elongated forming section, means extending into and rotatably supporting the closure cap to move it in a path along said elongated forming section to spin the lower edge of the cap inwardly into a substantially horizontal flange, a second elongated forming section, devices for subsequently extending into and rotatably supporting the closure cap and moving it along said elongated forming section to spin said flange upwardly and outwardly against the side of the cap to form an inturned bead or wire edge, and mechanism for centering a blank on said means and removing it from said means onto one of said devices.

16. In a device for forming an inturned bead on a closure cap or similar article, the combination of means for spinning the lower edge of the cap blank inwardly into a substantially horizontal flange, devices for subsequently spinning said flange upwardly and outwardly against the side of the cap blank to form an inturned bead or wire edge and mechanism for transferring the cap blank from said means to said devices and a drive for operating said means and said devices in timed relation with respect to each other.

17. The method of forming an inturned bead or wire edge at the bottom of a closure cap blank having a substantially cylindrical lower part, which method comprises simultaneously rotating the cap and moving it along a portion of an orbit, applying pressure in a direction substantially radially inwardly of the cap blank to spin a portion of the lower cylindrical part of the cap blank into an inturned flange and subsequently completing the bead by simultaneously rotating the cap blank and moving it along a portion of a different orbit and applying pressure substantially outwardly radially of the cap blank to fold said inturned flange against the skirt of the cap.

18. The method of forming an inturned bead or wire edge on a closure cap or similar article, which method comprises moving a cup-shaped blank having a cylindrical lower part along a portion of an orbit and simultaneously rotating the blank and spinning the lower edge thereof inwardly into an inturned substantially horizontal flange and moving said blank along a portion of a different orbit and simultaneously rotating the blank and spinning said inturned flange upwardly and outwardly against the side of the blank to form an inturned bead or wire edge.

19. The method of forming an inturned bead or wire edge in the manufacture of a closure cap

or similar article, which method comprises forming a cup-shaped blank with an annular substantially-cylindrical band at the bottom offset outwardly, spinning the lower edge of said band inwardly to form an inturned flange by pressure applied in a direction substantially radially inwardly of the cap while moving the cap along a portion of an orbit, continuing the movement of the cap into a different orbit completing the bead by applying pressure to said inturned portion radially outwardly of the cap while the cap is moving along a portion of said orbit and forming a screw thread in said cap while moving in one of said orbits.

20. The method of forming a thread and in-turned bead or wire edge in the manufacture of a closure cap or similar article, which method comprises moving a cup-shaped blank in a path, rotating the blank during said movement to spin inwardly the lower edge of the cap blank, forming a thread in the cap while the rotating blank is moving in said path and, subsequent to the continuous operation of forming the thread and the inturned edge, moving said blank in a different path and completing the formation of the bead by forcing said inturned edge upwardly and outwardly.

21. The method of forming an inturned bead or wire edge in the manufacture of a closure cap or similar article, which method comprises moving a cup-shaped cap blank having a cylindrical lower part in a plane, rotating the cap blank about an axis perpendicularly to the plane of movement, spinning the lower edge of the cylindrical part of the cap blank inwardly into an inturned edge to partially form a bead on the bottom of the skirt forming a thread in the cap blank, and thereafter completing the formation of the bead in the cap after the formation of the thread by spinning said inturned edge outwardly in a continuous operation.

22. In a device of the class described, the combination of means for feeding blanks for closure caps, a chuck adapted to enter and carry a blank for a closure cap, said chuck being of a smaller diameter than the blank, means cooperating with the chuck for forcing inwardly a portion of the blank, expansible means including a freely mounted ring member associated with said chuck, and a pin extending axially of the chuck with a shoulder thereon, said pin through the intermediation of said shoulder being adapted to expand said expansible means to center a cap blank on said chuck when the pin is moved in an axial direction to prevent interlocking of the inwardly forced part with the chuck.

23. In a device of the class described, the combination of means for feeding blanks for closure caps, a chuck adapted to enter and carry a blank for a closure cap, said chuck being smaller than the blank, means cooperating with said chuck to force the flange of the blank inwardly to form a screw projection therein and means associated with said chuck and adapted to center said blank on the chuck at the time of the removal to prevent the screw means from interlocking with parts of the chuck during the removal operation.

24. In a device of the class described, the combination of means for feeding blanks for closure caps, said blanks having an inturned flange at the bottom thereof, a chuck adapted to enter and carry a blank, said chuck being smaller than the blank, means for rotating said chuck about its axis and for moving it in an orbit, and means cooperating with the chuck to apply pressure radially outwardly against said flange to force said flange upwardly and outwardly against the inside of the flange of the blank during said rotary and orbital movement to form an inturned bead on the blank.
